US00D941872S

(12) **United States Design Patent** (10) Patent No.: **US D941,872 S**
(45) Date of Patent: **** Jan. 25, 2022**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Patrick Lee Coffman**, San Francisco, CA (US); **Raymond Sepulveda**, San Jose, CA (US)

(73) Assignee: **Apple Inc.**, Cupertino, CA (US)

(***) Term: **15 Years**

(21) Appl. No.: **29/800,625**

(22) Filed: **Jul. 22, 2021**

Related U.S. Application Data

(63) Continuation of application No. 29/740,329, filed on Jul. 2, 2020, now Pat. No. Des. 926,215, which is a continuation of application No. 29/706,105, filed on Sep. 18, 2019, now Pat. No. Des. 889,503, which is a continuation of application No. 29/683,939, filed on Mar. 18, 2019, now Pat. No. Des. 862,508, which is a continuation of application No. 29/642,082, filed on

(57) **CLAIM**

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

The sole FIGURE is a display screen or portion thereof with graphical user interface showing our new design.

The peripheral dashed broken lines depict a display screen or portion thereof, and form no part of the claimed design. The dotted broken lines depict boundaries which form no part of the claimed design and the faded portions within the dotted broken lines form no part of the claimed design.

**1 Claim, 1 Drawing Sheet
(1 of 1 Drawing Sheet(s) Filed in Color)**

Related U.S. Application Data

Mar. 27, 2018, now Pat. No. Des. 849,780, which is a continuation of application No. 29/582,325, filed on Oct. 27, 2016, now Pat. No. Des. 815,140.
